EXTERIOR LIGHTING FIXTURE

Donald E. Husby, Fairview Park, Ohio, and Edmund L. Izzi, Pittsburgh, Pa., assignors to Westinghouse Electric Corporation

Filed Apr. 21, 1970, Ser. No. 22,547

Term of patent 14 years

Int. Cl. D26—03

U.S. Cl. D48—31

FIG. 1 is a side elevational view of an exterior lighting fixture showing our new design;

FIG. 2 is an enlarged front elevational view thereof;

FIG. 3 is an enlarged side elevational view thereof;

FIG. 4 is an enlarged top plan view thereof;

FIG. 5 is an enlarged bottom plan view thereof.

The lamp post is broken away in FIG. 1 to show indeterminate length and fragmentarily shown in FIGS. 2 through 5 for convenience of illustration.

A characteristic feature of our design resides in the asymmetrical mounting which produces a tilted fixture orientation.

We claim:

The ornamental design for an exterior lighting fixture, substantially as shown and described.
